US00D690652S

(12) **United States Design Patent**
Anderson et al.

(10) **Patent No.:** US D690,652 S
(45) **Date of Patent:** ** Oct. 1, 2013

(54) **ELECTRICAL CORD END**

(75) Inventors: **Jason W. Anderson**, Howick (NZ); **Nils G. Johannessen**, Westmere (NZ)

(73) Assignee: **Actuant Corporation**, Menomonee Falls, WI (US)

(**) Term: **14 Years**

(21) Appl. No.: **29/399,555**

(22) Filed: **Aug. 16, 2011**

(51) **LOC (9) Cl.** 13-03

(52) **U.S. Cl.**

USPC **D13/146**

(58) **Field of Classification Search**

USPC D13/107-109, 118-119, 133, 146, D13/147, 154, 184, 199; D23/226; 320/104, 320/107, 108, 109, 110, 111, 112, 113, 114, 320/115

(57) **CLAIM**

The ornamental design for an electrical cord end, as shown and described.

DESCRIPTION

FIG. 1 is a front perspective view of an electrical cord end showing our new design;

FIG. 2 is a left side elevational view thereof;

FIG. 3 is a right side elevational view thereof;

FIG. 4 is a top elevational view thereof;

FIG. 5 is a bottom elevational view thereof;

FIG. 6 is a rear elevational view thereof; and,

FIG. 7 is a front elevational view thereof.

The broken line portion of the figure drawings is included for the purpose of illustrating environment and forms no part of the claimed design.
